UNITED STATES PATENT OFFICE.

ALONZO ALDRICH, OF BELoit, WISCONSIN.

PAPER-MAKING MACHINE.

Application filed February 14, 1924. Serial No. 692,642.

My invention relates to machines for making paper and particularly to paper making machines commonly known as Fourdrinier machines.

5 One of the objects of the invention is to provide a simple, practical and effective construction of paper making machine.

Another object of the invention is to arrange for the effective and advantageous 10 mounting and movement of certain parts of the machine, particularly the table rolls.

Another object of the invention is to arrange for the shaking of the table rolls without shaking the brest roll.

15 Another object of the invention is to secure this result in a Fourdrinier machine particularly adapted and constructed to permit the lateral removal of the table to allow ready and convenient application of a new 20 wire, and also in a machine which is vertically adjustable and also one in which the brest roll is adjustable longitudinally of the table to facilitate the application of the new wire.

25 In the accompanying drawings Fig. 1 is a side elevation of the end portion of a table of a Fourdrinier machine embodying my present invention;

Fig. 2 is a cross section of the same on an 30 enlarged scale;

Fig. 3 is a plan view of the portion of the table shown in Fig. 1.

Referring to the drawings, I show a table 1 for a Fourdrinier machine, comprising 35 longitudinally extending side main frame members 2—2. Table rolls 3—3 are mounted above the side members 2—2, a brest roll 4 is arranged at the end of the table and a wire 5 is shown arranged over the table rolls 40 3 and brest roll 4.

In accordance with my invention the table rolls 3—3 are arranged to be shaken without shaking the brest roll 4 and to such end I show said table rolls 3 mounted on side 45 rails 6—6, which latter are in turn mounted on the side frame members 2—2 through the medium of vertically arranged spring members 7—7 which are preferably made of wood which gives the desired spring-like 50 action, permitting said rolls 3—3 to be shaken.

As a preferred arrangement the rails 6—6 are formed in a plurality of parts, as for example, three parts, 6^a, 6^b and 6^c, whereof 55 the end parts 6^a and 6^c are pivoted by fixed pivots 7^a and 7^c and the parts 6^a and 6^b are

pivoted together at 8^a and the parts 6^b and 6^c pivoted together at 8^b, whereby a jointed table roll rail arrangement is made, having fixed pivoted ends and jointed between those ends to permit shaking of the table rolls.

As an arrangement for shaking the table rolls I show reciprocating members 9—9 which are connected with the central rail member 6, and also connected with shoes 10—10 on vibratory posts 11 vibrated by suitable power means to secure the desired shaking effect.

The brest roll 4 is preferably mounted so as to permit of its adjustment longitudinally 70 of the table and to such end is mounted in a sliding frame 12 having side members 13 sliding lengthwise of the side frame members 1 and having slots 14 cooperating with bolts 15—15 to effect the proper guiding of 75 said frame.

As a means for longitudinally adjusting said frame, I show a hand wheel 16 having connection through gears 17, 18 and 19 with racks 20 on said sliding frame 12, whereby 80 a turning of the handle 16 will effect a longitudinal adjustment of the brest roll 4.

The entire table is preferably made vertically adjustable, as by providing the brest roll end with hooks 24 over which cables 25 85 may pass, the cables 25 being understood to be run up to windlasses or other lifting device for elevating and lowering said cables and thereby elevating and lowering the table.

Thus the arrangement permits the shaking of the table rolls independently of the brest roll and while the brest roll is held stationary if desired, and also permits the longitudinal adjustment of the brest roll independent of the table rolls, and so allows 90 the brest roll to facilitate the application of a new wire in such an arrangement as shown wherein the table rolls are shaken.

The sliding brest roll with the sliding 100 mounting or frame therefor is shown, described and claimed by me in my Patent No. 1,494,537, issued May 20, 1924, paper making machines, and so said sliding frame and arrangement is not claimed per se in this application. Certain features of the 105 roll mounting disclosed herein are disclosed and claimed in my copending application Serial No. 595,258, filed October 18, 1929, paper making machines, and so are not claimed per se herein. Reference is also 110 made to my Patent Reissue No. 16,075, issued May 19, 1925.

It will be understood that changes and modifications may be made without departing from the spirit of the invention.

What I claim is:

5. 1. A Fourdrinier machine having a table provided with shakable table rolls and a 60 slidable brest roll.
2. A Fourdrinier machine having a table provided with table rolls and also with a brest roll, means for mounting the table 65 rolls to permit shaking movement of the table rolls without shaking the brest roll and means for sliding the brest roll longitudinally of the table.
15. 3. A Fourdrinier machine having a table provided with table rolls and also with a brest roll, means for mounting the table rolls to permit shaking movement of the table rolls without shaking the brest roll 70 and means for sliding the brest roll longitudinally of the table, said table rolls being shakable irrespective of the position of the brest roll in sliding adjustment.
25. 4. A Fourdrinier machine having a table provided with table rolls and means for mounting said table rolls to permit shaking movement, said mounting means comprising jointed side rails whereof the several portions each supports a portion of the 75 rolls.
30. 5. A Fourdrinier machine having a table provided with table rolls and means for mounting said table rolls to permit shaking movement, said mounting means comprising jointed side rails whereof the several portions each supports a portion of the rolls, said jointed side rails having their remote ends mounted on fixed pivots and their intermediate ends pivotally connected 80 with one another.
40. 6. A Fourdrinier machine having a removable table provided with independently shakable table rolls, and also having a slidable brest roll.
45. 7. A Fourdrinier machine having a vertically adjustable table provided with independently shakable table rolls, and also having a slidable brest roll.
- pendently shakable table rolls, and also having a slidable brest roll.
8. A Fourdrinier machine having a vertically adjustable and removable table provided with independently shakable table 85 rolls and also having a slidable brest roll.
9. A Fourdrinier machine having a removable table provided with a longitudinally slidable brest roll and independently shakable table rolls.
10. A Fourdrinier machine having a vertically adjustable and laterally removable table provided with a slidable brest roll and independently shakable table rolls.
11. A Fourdrinier machine having a vertically adjustable and laterally removable table provided with a slidable brest roll and independently shakable table rolls, in combination with means for shaking the table rolls without shaking the brest roll 90 and means for longitudinally sliding the brest roll.
12. A Fourdrinier machine having a removable table provided with independently shakable table rolls and also having a non-shakable slidable brest roll.
13. A Fourdrinier machine having a vertically adjustable table provided with independently shakable table rolls and also having a non-shakable brest roll movable 95 in a direction longitudinally of the table.
14. A Fourdrinier machine having a vertically adjustable and removable table provided with independently shakable table rolls and also having a non-shakable brest roll mounted for sliding movement longitudinally of the table.
15. A Fourdrinier machine having a vertically adjustable table provided with independently shakable table rolls and also provided with a non-shakable slidable brest roll.

In witness whereof, I hereunto subscribe my name this 30th day of January A. D., 1924.

ALONZO ALDRICH.
